UNITED STATES PATENT OFFICE.

SEBASTIAN RANLEY AND JOHN A. SCHIRACK, OF ST. HENRY, OHIO.

FOLDING DOOR.

1,008,367.

Specification of Letters Patent. Patented Nov. 14, 1911.

Application filed March 6, 1911. Serial No. 612,496.

To all whom it may concern:

Be it known that we, SEBASTIAN RANLEY and JOHN A. SCHIRACK, citizens of the United States, residing at St. Henry, in the 5 county of Mercer and State of Ohio, have invented certain new and useful Improvements in Folding Doors, of which the following is a specification.

This invention relates to a door to form 10 a portion of a buggy top, and has particular reference to new and useful improvements in the swinging door described and shown in our Patent No. 968,193, of August 23, 1910.

The door illustrated in our above referred 15 to patent comprised a lower swinging portion, which when the door is opened, is swung inwardly and upwardly to clear the front wheel. The disadvantage encountered in connection with this construction is that 20 the swinging portion does not lie flat against the body portion of the door but stands out and inconveniences the passenger when entering or leaving the vehicle.

An important object of this invention is 25 to provide a door of the above character, having a portion connected to its lower end, which portion is adapted to be swung inwardly and upwardly to clear the front wheel and which is so constructed that the 30 same will correspond to the shape of and lie flat against the body portion of the door, to occupy the minimum amount of space when the door is open.

Other objects and advantages of this invention will be apparent during the course 35 of the following description.

In the accompanying drawings forming 40 a part of this specification, and in which like numerals are employed to designate like parts throughout the same, Figure 1 is a side view of our improved door, the swinging portion thereof being in its lower position, Fig. 2 is a transverse vertical section taken on line 2—2 of Fig. 1, Fig. 3 is a view 45 similar to Fig. 1, the swinging portion being in its raised position, and, Fig. 4 is a vertical transverse sectional view taken on line 4—4 of Fig. 3.

In the drawings wherein is illustrated a 50 preferred embodiment of our invention, a door is shown, comprising an upper body portion 1 adapted to be secured to the top of a vehicle through the medium of hinges 2. This door is capable of oscillating in a 55 horizontal plane in an outwardly direction, as illustrated in connection with the door

shown in our Patent No. 968,193, of August 23, 1910. The body portion 1 is provided near its upper end with an opening formed therethrough, which is spanned by a section 60 of glass 3 or other suitable transparent material. The door further comprises a triangular section 4, which is rigidly connected with the lower end of the body portion 1 and extends inwardly therefrom to form an 65 angle 5 with said body portion. The door further comprises a swinging portion 6, formed of two sections 7 and 8, which are rigidly connected and arranged to form an outer angle 9, which is equal to the inner 70 angle 5. The section 7 is triangular and is adapted to coincide with the triangular section 4, when placed thereon. (See Figs. 3 and 4.) The section 8 has preferably the shape, 75 as shown, and is substantially vertically disposed when occupying either its elevated or lower position. The lower portion 6 is pivotally connected with the body portion of the door by hinges 10, which are suitably secured to the triangular sections 4 and 7, 80 adjacent their abutting longitudinal edges. A strap 11 is provided, the upper end of which is secured to the buggy and the lower end secured to the section 8, as shown at 12.

In the use of our door, when the same is 85 swung outwardly, the strap 11 will oscillate the portion 6 inwardly and upwardly to clear the front wheel. This portion will then occupy the minimum amount of space, the section 7 being flat upon the section 4 and 90 the section 8 lying flat against the body portion 1, which results from having the angles 5 and 9 equal.

We wish it understood that the form of 95 our invention herewith shown and described is to be taken as a preferred example of the same, and that certain changes in the shape, size and arrangement of parts may be resorted to without departing from the spirit of the invention or the scope of the sub- 100 joined claim.

Having thus described our invention, we claim:

A door of the character described, comprising a body portion having a triangular section connected with the lower end thereof and extending inwardly therefrom to form an angle therewith, a portion pivotally connected with said section and comprising upper and lower sections which are rigidly 105 connected for forming an angle equal to the first named angle, the upper section being 110

in the form of a triangle and adapted to coincide with the first named triangular section, so that said portion may lie flat against the first named triangular section 5 and the body portion, and means to swing the second named portion upwardly and inwardly upon the swinging of the door outwardly.

In testimony whereof we affix our signatures in presence of two witnesses.

SEBASTIAN RANLEY.
JOHN A. SCHIRACK.
